FLOOD VALVE ASSEMBLY

John M. Chamberlin, Laurel, Md., assignor, by mesne assignments, to the United States of America as represented by the Secretary of the Navy

Filed Jan. 12, 1962, Ser. No. 165,972

11 Claims. (Cl. 102—13)

This invention relates to a flooder for a marine mine and the like and more particularly to a flooder for a floating mine in which electroresponsive explosive means are employed to rupture the flooder as the mine is disarmed thereby to cause the mine to sink within the water as the result of water admitted to the interior of the mine.

In devices of this character heretofore devised it has been the usual practice to assemble the flooder with the mine casing prior to storage thereof within a warehouse or transportation of the mine to the launching vessel, as the case may be. In either event the electroresponsive explosive means was subject to premature operation by reason of the fact that the two lead-in wires connected thereto were not shunted and the device therefore would be actuated prematurely in the event that the lead-in wires should become connected to a source of potential.

In accordance with the present invention the foregoing disadvantages are overcome by providing a flooder device which is merely plugged in to the mine casing just prior to planting of the mine and the lead-in wires to the detonating elements disposed therein are short circuited until the device has been plugged into the mine. Furthermore, the necessary electrical connections between the lead-in wires and the plug in elements for establishing an external electrical connection thereto are made without employing a soldering operation. The device of the present invention possesses all of the advantages of the prior art devices and none of the foregoing disadvantages.

One of the objects of the present invention is to provide a new and improved flooder for a marine mine.

Another object is to provide an electroresponsive flooder for an underwater marine weapon in which means are provided for short circuiting the electroresponsive detonating element therein until the flooder has been plugged into the weapon.

A still further object is to provide a flooder for a mine in which the electroresponsive detonating element encapsulated therein is short circuited until the flooder has been plugged into the mine, the electrical connection between the electroresponsive detonating element and the plug-in electrical terminals being achieved by new and improved connecting means in which a soldering operation is not involved.

Various other objects, improvements and advantages will be apparent from the following description taken in connection with the accompanying drawings of which:

FIG. 1 is a view partly in section of the flooder of the present invention plugged into and sealed to a mine casing;

FIG. 2 is an enlarged view partially broken away and partially in section of the device of FIG. 1 in an assembled position with the mine;

FIG. 3 is an enlarged view taken along line 3—3 of FIG. 1;

FIG. 4 is a fragmentary view of the flooder prior to insertion within the mine casing;

2

FIG. 5 is a greatly enlarged view in perspective and partially broken away of one of the spring terminal elements of FIG. 4; and

FIG. 6 illustrates diagrammatically a circuit arrangement suitable for use with the device of the present invention for sinking a subfloating mine.

Referring now to the drawings for a better understanding of the invention on which like reference numerals are employed to designate like parts throughout the several views, and more particularly to FIG. 1 thereof, there is shown thereon a flooder in accordance with a preferred embodiment of the invention and designated generally by the numeral 10. The device comprises a body 11 of generally cylindrical configuration having two outwardly extending portions 12 configured generally as shown and having a notched or grooved portion 13 therebetween, each of the ends of the grooved portions 13 being contiguous with a longitudinal groove 14 extending along the outer periphery of the device for a substantial portion of the length thereof. A pair of grooved portions 15 are provided in the body for receiving and retaining a pair of contact spring members 16 and 17, respectively disposed therein in such manner that the spring members are in mutual engagement as shown on FIG. 4 prior to plugging the flooder into the mine casing. The lower ends of the spring members 16 and 17 are each provided with a generally U-shaped clamping portion 18 adapted to grip an interior face of the groove 15 and maintain the spring member in an assembled position with respect to the body member. There is also provided, on the lower end portion of each spring member, a tab 19 adapted to engage and grip an exposed end portion of a pair of lead-in wires for establishing an electrical connection to a pair of electro-responsive detonators or squibs 21 respectively connected thereto in such manner that the detonators are connected in parallel across the spring members 16 and 17. The detonators 21 are respectively disposed within recessed portions 22 of the body, a pair of apertures 23 being provided within the body in communication with the recessed portions 22 whereby the pair of lead-in wires from each detonator may be disposed within a different one of the apertures to permit the lead-in wires to extend to the spring members 16—17 for connection thereto. The body 11 is provided with a register 24 at the lower end thereof for establishing a connection with a cap 25 configured externally through a cylinder of the same diameter as the cylinder of the body and having a circular radially extending flange 26 at the lower portion thereof. The interior of the cap 25 is hollowed out as at 27 to form an explosion chamber about the lower ends of the detonators 22 when the cap is in the assembled position. The casing 28 of the mine to be flooded is provided with a cylindrical support 29 welded interiorly thereto as at 31 and having a bore 32 therein in alignment with a corresponding bore 33 of the same diameter formed within the casing 28 of the mine. The cylindrical support 29 is threaded as at 34 to receive a hollow nut-like element 35 securely threaded therein. The nut-like element is provided with a bore 36 adapted to slidably receive the body 11 and threaded as at 37 to engage a circular clamping member 38 threaded therein, the clamping member being provided with a bore 39 of substantially the same diameter as body 11 and a circular shoulder

41 abutting the bore 39 adapted to receive and be engaged by flange 26 of the body 11 and securely clamp the flooder in the assembled position within the mine when the clamping member is tightened by a suitable tool engaging the slots 42 within the clamping member. A flexible seal 43 is provided between the upper annular surface of the clamping member 38 and the lower surface of nut-like element 35 thereby to effect a watertight seal between the clamping member 38 and the interior of the mine. An O-ring 45 is provided between the clamping member 38 and the body 11 substantially as shown to provide a watertight seal therebetween.

On the upper surface of the nut-like element 35 is provided a pair of upstanding supports 46 diametrically disposed about the apertured portion of the element 35 and each having a flanged end portion 47 extending within bore of the element 35 sufficient to engage the grooves 14 of the body 11, FIG. 3, and thereby provide means for insertion of body 11 within the nut-like element 34 in a predetermined aligned position with respect to the supports 46. A terminal board or mounting plate 48 is secured to the supports 46 as by the screws 49 illustrated. The terminal board is also provided with three tapered contact plugs 51 arranged in a row for engaging the springs 16 and 17 of the flooder when the flooder is in the assembled position shown on FIG. 2. Spring member 17, it will be noted, is provided with a single upper contacting surface for engagement with the centrally located plug 51 when the flooder has been assembled in the mine. The spring member 16, it will be noted, is provided with a slot 52, FIG. 3, of less width than the width of the spring member 17 thereby to form a pair of contacting surfaces on the spring member 16 for engagement with the contacting surface of spring member 17 prior to the assembly of the flooder within the mine, the contacting surfaces being so configured that the three contacting surfaces will each engage a corresponding one of the contact plugs 51 when the flooder is assembled in the mine and thereby remove the short circuit from the detonators 21 and connect the detonators by way of conductors 53 and 54 to a flooding control circuit 55, the electrical connections between the conductor 53 and outer contact plugs 51 and between conductor 54 and center contact plug 51, respectively, being achieved by a pair of metallic connector strips 50 connected thereto substantially as shown. The body 11 and cap 25 therefor are composed of insulating materials suitable for the purpose, such, for example, as Bakelite or any of the synthetic plastic varieties thereof suitable for the purpose of sufficient strength to maintain the parts immovably in the assembled position prior to firing of the flooder and of insufficient strength to prevent destruction of the flooder to an extent sufficient to cause the mine to be flooded in response to the operation of the detonators 21.

The flooder may be operated by any suitable means, such, as for example, as the circuit means diagrammatically illustrated on FIG. 6 on which is shown flooder 10 connected by conductors 53 and 54 to a flooding control mechanism 55 and a hydrostatically actuated switch 56, the circuit including a battery 57. The flooding control mechanism may be of any type suitable for the purpose such, for example, as the flooding control mechanism disclosed in Patent No. 2,705,919 dated April 12, 1955, to H. W. Semon.

Briefly stated in summary, the present invention contemplates the provision of a new and improved flooder for an underwater marine weapon which is adapted to be plugged into the mine after the mine has been assembled and in which means are provided for short circuiting the electroresponsive detonator elements therein until the flooder has been plugged into the mine and in which the connection between the detonating elements and the plug in contact elements carried by the flooder are achieved

by a frictional clamp device and without the utilization of a soldering operation.

Whereas the invention has been described with reference to one example thereof which gives satisfactory results, it is not so limited as it will be apparent to one skilled in the art, after understanding the invention that various changes and modifications may be made without departing from the spirit and scope of the invention and it is intended therefore, in the appended claims to cover all such changes and modifications.

What is claimed as new and desired to be secured by Letters Patent of the United States is:

1. A device for flooding a floating mine with water comprising a casing secured to the mine, said casing having a normally sealed port in communication with the water, an explosion chamber adjacent said port, a pair of electroresponsive detonators within said casing in communication with said explosion chamber, a pair of normally closed spring contacts carried by said casing, lead-in wires interconnecting the detonators in parallel connection with said spring contacts, at least two tapered terminal pins fixed interiorly to the mine in a manner to engage said spring contacts and establish an external operative firing circuit to the detonators, the spring contacts being moved to an unshorting position by the tapered terminal pins as the springs are engaged thereby, and means for applying an impulse to the firing circuit thereby to unseal said port and admit water into the interior of the mine.

2. A flooding device according to claim 1 in which the spring contacts are provided with a tab in an end portion thereof to frictionally engage an end portion of said lead-in wires and maintain electrical contact therewith when the spring contacts are assembled on said casing.

3. A flooding device according to claim 2 in which the casing is provided with a pair of slots within an end portion thereof within which the spring contacts are forced, each of said spring contacts being provided with a generally U-shaped end portion for engagement with a wall of said slots in a manner to frictionally maintain the contact springs in assembled relation therewith and establish good electrical contact with the ends of said lead-in wires.

4. A flood valve according to claim 3 including means for aligning the closed spring contacts with the tapered terminal pins prior to engagement therewith.

5. A flood valve according to claim 4 including a pair of posts for supporting the tapered terminal pins in fixed relation to the mine casing, each of said posts having a flange formed thereon, and the aligning means includes a pair of longitudinal grooves formed exteriorly on the casing for engagement with said flanges when the spring contacts are aligned with the tapered terminal pins.

6. A flood valve according to claim 5 including an annular device threadedly connected to the mine at an interior portion thereof for engaging said casing in a manner to maintain the flood valve in an assembled position within the mine.

7. The flood valve of the claim 6 including means for effecting a watertight seal between the casing and the outer surface of the mine.

8. The flood valve of claim 7 in which the casing is composed of a rigid plastic material.

9. A flood valve assembly for flooding a floating mine with water comprising a casing composed of a rigid plastic material secured to the mine, a pair of electroresponsive detonators within said casing, a pair of normally closed spring contacts carried by said casing, lead-in wires interconnecting the detonators in parallel connection with said spring contacts to normally short-circuit the detonators, and means for opening said contacts and establishing an external operative firing circuit to the detonators.

10. In a flooder for a floating mine, in combination, a casing secured to the mine, a pair of electroresponsive detonators within said casing, a pair of normally closed

spring contacts carried by said casing, lead-in wires interconnecting the detonators in parallel connection with said spring contacts to normally short-circuit the detonators, and means comprising a plurality of tapered contact pins for engaging said spring contacts to open said contacts, and adapted to establish an electrical connection between one of said pins and one of said spring contacts and to establish another electrical connection between another of said pins and the other spring contact, thereby unshorting the spring contact-detonator circuit and establishing an external operative firing circuit to the detonators.

11. The flooder of claim 10 in which one of said

spring contacts is provided with a slot of less width than the width of the contacting surface of the other of said spring contacts, whereby one of said plurality of tapered contact pins passes through said slot to engage only the other of said spring contacts, while the other of said plurality of pins engage only the slotted spring contact.
